BURSTER FOR CONTINUOUS FORM PAPER

Dana W. Mox, Glenview, Ill., assignor to Uareo Incorporated, Barrington, Ill., a corporation of Illinois

Filed Jan. 31, 1962, Ser. No. 68,618

Term of patent 14 years

(Cl. D55—1)

FIG. 1

FIG. 2

FIG. 3

FIG. 4

FIG. 5

FIG. 6

FIG. 1 is an isometric view of the front and one side of a burster for continuous form paper embodying my new design, the doors being in an open position;

FIG. 2 is an isometric view of the rear and opposite side thereof;

FIG. 3 is a side elevational view of the right side thereof, the doors being in a closed position;

FIG. 4 is an elevational view of the left side thereof;

FIG. 5 is a front elevational view thereof;

FIG. 6 is a rear elevational view thereof;

FIG. 7 is a top plan view thereof.

I claim:
The ornamental design for a burster for continuous form paper, as shown and described.
